UNITED STATES PATENT OFFICE

JOHN M. KEENAN, OF TORONTO, ONTARIO, CANADA

PROCESS OF MAKING COLOR-PRINTING PLATES

No Drawing.

Application filed March 26, 1931. Serial No. 525,609.

This invention relates to the production of the half tone plates used in multi-color lithographing and printing processes. Ordinarily the plates are prepared from negatives taken by photographing the colored subject first through a green filter, then through a red filter and then, through a blue filter, and, in four color works, through a pale amber filter to produce the "black" plate. Thus "color separations" are obtained, that is negatives, one of which is supposed to represent all the yellow in the subject, another all the red and another all the blue, while the "black" plate represents the whole of the tones of the original in their proper relation to each other.

Unfortunately, however, it is mainly supposition, as light filters which will pass the rudimentary printing colors in their proper proportions are unattainable.

The result is that, when the plates produced from these "color-separation" negatives are prepared, a great deal of hand work is required to make each plate represent as truly as possible the values of the color which it represents.

In the case of photo-engraving this work comprises stopping out or "staging" parts of the plate which are sufficiently etched and "re-etching" by hand those parts insufficiently etched to bring out the proper value of the color. This work is done in stages until finished and afterwards proofs must be pulled, with all three or four impressions properly superimposed, in order to determine how accurately the colors of the original are produced. If the results are not satisfactory this goes on till the plates are satisfactory. This hand work takes a lot of the time of skilled and highly paid labor. For instance, from forty-five to sixty hours of time is an average for an ordinary job.

My object in the present invention is to obtain the proper values of the colors in the printing plates as far as possible by photo-mechanical means, though some small amount of hand work may in some cases be necessary for the finest results, thus eliminating nearly all the hand "staging" and "re-etching" now required on the printing plates themselves.

This is effected in the following manner. It

appears that the green color filter lets through some blue light, that the red color filter also lets through some blue light, that the blue color filter lets through some red and some yellow light, and that the "black" negative, though taken through a pale amber filter does not give the tonal values of the original exactly enough. Therefore, to obtain substantially correct color values in the final positives, which are used as copy for the making of the color plates, or transparencies for use in the production of the replicas of the original copy, some means must be provided to cut-out the effects of the intrusive color when preparing a positive from a "color-separation" negative.

This is done by superimposing on the "color-separation" negative (yellow, red, or blue, as the case may be) a positive, or "cut-out" taken from the complementary "color separation" negative and then, by means of the camera, making a positive by means of light transmitted through the combination. This complementary positive or "cut-out" usually remains in position during part only of the time of exposure and then exposure is completed with light transmitted by the "color separation" negative only. As the complementary positive or "cut-out" represents color values complementary to those of the "color-separation" negative, it cuts down the effect of the transparency of the "color-separation" negative, where the complementary color has affected it, so that the positive printed from the combination has cut out of it the effect of the passage of the complementary color which passes the filter and affected the original "color-separation" negative. In practice I employ a "cut-out" representing blue with a yellow "color-separation" negative, a "cut-out" representing blue with a red "color-separation" negative, and employ with a blue "color-separation" negative, first a "cut-out" representing red, and then, preferably, a "cut-out" representing yellow (each for part of the time of exposure), and with the "black" negative all three "cut-outs" successively (each for part of the time of exposure).

In the case of the making of the positives

from the blue and the black "color-separation" negative the exposure may also be for part time without using a "cut-out".

The color separation negatives and positives are, of course, applied face to face so that the films are in substantially the same focal plane.

With the method of overlaying the "color-separation" negatives with "cut-out" positives, made from complementary "color-separation" negatives, any tonal effects desired may be produced, as the cut-out effect is readily varied by varying the ratio of the time exposure of the final positive, with a "cut-out" in position, to the total exposure.

This process demands perfect registration of a "color-separation" negative, and the "cut-out" employed, and any known apparatus may be employed for this purpose.

The final positives are used in any known manner to produce the printing plates used in making replicas of the original copy.

What I claim as my invention is:

1. In a process of making color-printing plates the steps which consist in making ordinary "color-separation" negatives from an original representing the three primary printing colors red, yellow and blue; making positives from said negatives; superimposing a positive taken from the blue color separation negative on the yellow color separation negative to serve as a corrective "cut-out"; superimposing a positive taken from the blue color separation negative on the yellow color separation negative to serve as a corrective "cut-out"; superimposing on a blue color separation negative a positive taken from a color-separation negative representing light of a longer wave length; and, with a camera, producing a positive of each combination by light transmitted therethrough.

2. In a process of making color-printing plates the steps which consist in making ordinary "color-separation" negatives from an original representing the three primary printing colors red, yellow and blue; making positives from said negatives; superimposing a positive taken from the blue color-separation negative on the yellow color-separation negative to serve as a corrective "cut-out"; superimposing a positive taken from the blue color-separation negative on the yellow color-separation negative to serve as a corrective "cut-out"; superimposing on a blue color separation negative first a positive taken from the yellow "color-separation" negative and subsequently, after removing the said positive, a positive taken from the red "color-separation" negative; and, with a camera, producing positives from the combinations by light transmitted therethrough, the exposure in the case of the blue "color-separation" negative being for part time with the yellow "cut-out" in place and part time with the red "cut-out" in place.

3. A process of making color printing plates as set forth in claim 2 in which the final positive taken from each "color-separation" negative is exposed for part time without a "cut-out" positive superimposed. 70

4. In a process of making color-printing plates the steps which consist in making ordinary "color-separation" negatives from an original representing the three primary printing colors red, yellow and blue and also a so-called "black" negative; making positives from each "color-separation" negative to serve as a corrective "cut-out"; making final positives from the three "color-separation" negatives and from the "black" negative, with a camera by transmitted light; and using said "cut-out" positives to correct the color values in the last-mentioned positives by super-imposition on the negatives during exposure. 80

5. A process according to claim 4 in which the exposure of the final positives is made for part time with the use of the "cut-out" positives and part time without. 85

6. A process according to claim 4 in which the final positives made from the blue "color-separation" negative and the "black" negative are made, using both the yellow and red "cut-out" positives in the case of the blue "color-separation" negative and all three "cut-out" positives in the case of the "black" negative. 90

7. A process according to claim 4 in which the final positives made from the blue "color-separation" negative and the "black" negative are made, using both the yellow and red "cut-out" positives in the case of the blue "color-separation" negative and all three "cut-out" positives in the case of the "black" negative and in which the exposure of the final positives is made for part time with the use of the "cut-out" positives and part time without. 100

Signed at Toronto, Canada, this 19th day of January, 1931.
